UNITED STATES PATENT OFFICE.

SAMUEL LEVINE, OF BROOKLYN, NEW YORK, ASSIGNOR TO S. & H. LEVINE, OF NEW YORK, N. Y., A COPARTNERSHIP.

HOOK-LINK FOR EXPANSIBLE BRACELETS, &c.

1,282,442.

Specification of Letters Patent. Patented Oct. 22, 1918.

Application filed February 23, 1918. Serial No. 218,670.

To all whom it may concern:

Be it known that I, SAMUEL LEVINE, a citizen of the United States, and a resident of the borough of Brooklyn, county of 5 Kings, city and State of New York, have invented certain new and useful Improvements in Hook-Links for Expansible Bracelets, &c., of which the following is a specification.

My improvements relate to hook links for 10 expansible bracelets and the like, which have heretofore been made slidable with relation to their casings in a manner similar to that in which the expansible links of the chain have been constructed. This former construction necessitates the partial withdrawal 15 of the slidable coupling section of the hook link in order to bring the snap jaws into operative position for attachment to or withdrawal from a watch loop or similar object, and this partial withdrawal exposes the shank of the snap hook to danger of fracture by reason of undue strain, carelessness, or accident during manipulation.

It is the object of my invention to obviate 20 this difficulty, and to afford a simple, inexpensive hook link in which lightness, strength and rigidity of structure is attained in such manner that the shank of the snap hook is reinforced and sustained against undue strain or pressure, at the same time rendering the coupling parts convenient and effective in manipulation and use.

The invention consists in the specific construction and arrangement of parts described and claimed herein, a distinctive feature being a strap or transverse bar extending from one side of the shell to the other and engaging a shoulder on the shank of the snap hook in such manner as to hold said shank rigidly in position and reinforce and sustain it at or adjacent to the point of greatest danger of fracture from overstrain, all as hereinafter more fully set forth.

In the accompanying drawings; 45 Fig. 1, represents my improved hook link as attached to an expansible bracelet chain of well known construction;

Fig. 2, is a sectional elevation upon a larger scale, of my improved hook link;

Fig. 3, is a top view of the shell;

Fig. 4, is a longitudinal section thereof, taken upon plane of line 4—4, Fig. 3;

Fig. 5, is a side elevation of the hook section of the link;

Fig. 6, is a top view thereof;

Fig. 7, is a transverse section taken upon plane of line 7—7, Fig. 2;

Fig. 8, is a view similar to Fig. 2, showing an alternative but equivalent construction of my hook link;

Fig. 9, is a side elevation of the hook section shown in Fig. 8;

Fig. 10, is a top view thereof;

Fig. 11, is a top view of the shell shown in Fig. 8;

Fig. 12, is a section thereof, taken upon plane of line 12—12, Fig. 11;

Fig. 13, is a rear end view of the hook section shown in Fig. 9;

Fig. 14, is a transverse section taken upon plane of line 14—14, Fig. 8.

The coupling section C, of my improved hook link consists of a bar of suitable metal bent double, the ends being formed into the usual snap hook, consisting of the hook c, and detent c'. The shank c², of the hook c, is formed with a shoulder c³, upset as in Figs. 1, 2, and 5, or depressed as in Figs. 8, 9 and 10. This shoulder is provided for engagement with a reinforcing cross bar s, extending between and uniting the front portions of the side members or cheek pieces s', s', of the shell S, between which side members s', s', the main portion of the coupling section S, is positioned and secured, not only by the reinforcing cross bar s, but also by the inturned edges s², s², of the side members s', s', said inturned edges overlapping shoulders c³, c', formed by swaging the coupling section C, at the rear end or bight thereof, as shown more particularly in Figs. 6, 7, 10, 13 and 14. The inner side of the shank c², of the hook c, also rests against a cross bar s³, at the front end of the shell S, thereby locking the coupling member C, firmly in position on said shell, both at front and rear, so that the combined structure is essentially rigid and integral for all practical purposes.

The cross bar s⁴, at the inner end of the shell S, forms the means of copulation in the usual manner with one of a series of expansible links E, E, of any ordinary or well known construction.

Aside from the swaging of the inner end of the coupling member to form the shoulders c³, for engagement with the inturned edges s², of the side members s', of the shell S, the main feature of my invention is the reinforcing cross bar s, for engagement with

the shoulder c^3 , on the shank c^2 , of the hook c , whereby the latter is safeguarded against undue strain or violence during manipulation for attachment to or release from a 5 watch or similar loop or device.

The cross bar s , may be a separate piece rigidly secured to and across the upper edges of the side members s' , of the shell S , as in Figs. 2, 3 and 4, or it may consist of a 10 tongue protuberant from the edge of one side member s' , and extending to and under the inturned edge of the other side member s' , as in Figs. 8, 11 and 12, as may be preferred, the function in either case being 15 the same in that said cross bar s , acts in conjunction with the shoulder c^3 , on the coupling member C , to reinforce the shank c^2 , of the hook c , as hereinbefore set forth.

It is to be understood that while my 20 proved hook link is applicable to various uses it is designed more particularly as a substitute for the slideable hook section ordinarily employed in connection with expandable bracelets, which slideable hooks are particularly fragile of structure and subject to fracture by reason of lack of adequate support by the shells with which they are connected.

What I claim as my invention and desire 25 to secure by Letters Patent is,

1. A hook link of the character designated, comprising a coupling section formed with a snap hook having a shouldered shank, and a shell formed with side members flanking and attached to said coupling section, said shell being formed with a reinforcing cross bar engaging said shoulder on the shank of the snap hook, for the purpose described.

40 2. A hook link of the character designated, comprising a coupling section formed at its front end with a snap hook having a shouldered shank and at its rear end with laterally protuberant shoulders, and a shell 45 formed with side members having inturned edges which overlap said shoulders on the rear end of the coupling section and with a reinforcing cross bar engaging said shoulder on the shank of the snap hook, for the purpose described.

50 3. A hook link of the character design-

nated, comprising a coupling section formed at its front end with a snap hook having a shouldered shank and having its rear end swaged to form laterally protuberant shoulders, and a shell formed with side members having inturned edges which overlap said protuberant shoulders on the rear of the coupling section and with a reinforcing cross bar engaging said shoulder on the shank of the snap hook, for the purpose described.

4. A hook link of the character designated, comprising a coupling section formed at its front end with a snap hook having a shouldered shank and at its rear portion with laterally protuberant shoulders, and a shell formed with side members having inturned edges which overlap said shoulders on the rear end of the coupling section and with a reinforcing cross bar engaging said shoulder on the shank hook and also with a cross bar engaging the inner side of the shank of the snap hook, for the purpose described.

5. A hook link of the character designated, comprising a coupling section formed with a snap hook having a shouldered shank, and a shell formed with side members flanking and attached to said coupling section, the front portion of said shell being formed with a reinforcing cross bar engaging said shoulder on the shank of the snap hook and the rear portion of said shell being formed with a cross bar for engagement with a chain link or the like, for the purpose described.

6. A hook link of the character designated, comprising a coupling section formed with a snap hook having a shouldered shank adjacent one end upon its outer face, and a shell formed with side members flanking and attached to said coupling section, said shell being formed with a reinforcing cross bar engaging said shoulder and a cross bar engaging the inner side of the shank of said snap hook, whereby the coupling member is firmly locked in position on the shell both at the front and rear ends.

SAMUEL LEVINE.
